Atty's

UNITED STATES PATENT OFFICE.

FRIEDRICH MÜNZ, OF STUTTGART, GERMANY.

ELECTRIC STARTING MOTOR FOR INTERNAL-COMBUSTION ENGINES.

Application filed February 24, 1923. Serial No. 621,032.

To all whom it may concern:

Be it known that I, FRIEDRICH MÜNZ, a citizen of Germany, residing at Stuttgart, Germany, have invented certain new and useful Improvements in Electric Starting Motors for Internal-Combustion Engines (for which I have applied for a patent in Germany on Nov. 18, 1921, and Nov. 24, 1922), of which the following is a specification.

This invention relates to electric starting motors of the kind used in connection with explosion engines, and more particularly to the means for coupling the starting motor with the fly-wheel of the explosion engine for the purpose of starting the latter.

The object of the invention is to provide a means or device of the kind above indicated which will be of simple construction and absolutely reliable as regards its operation.

Further objects and advantages of the invention will be set forth in the detailed description which now follows:

25 In the accompanying drawing: Figure 1 is a longitudinal sectional view of the coupling device showing the adjacent parts of the starting motor and of the driven engine with the coupling members in disconnected position; Figure 2 is a sectional view of a modified construction of the coupling device.

Referring to the drawing in detail, and more particularly to Figure 1, the letter 35 *a* designates the armature shaft of an electric motor having one end of hollow form. A pinion *c* and threaded spindle *b'* are made in one piece so as to form an integral unit adapted to engage in and move lengthwise through a nut *i* inserted in the hollow shaft *a* and rigidly connected therewith, whereby the pinion *c* is moved into and out of mesh with the gear teeth of a fly wheel *g*. A strong spring *d* and a light spring *f* are 40 also encased in the hollow shaft and are confined between a flange *o* on the spindle *b'* and the nut *i* whereby to normally retain the spindle *b'* in its retracted position. As shown in the drawing the spring *d* is 45 fully extended and the spring *f* is partially extended whereby the initial movement of the spindle *b'* is only opposed by the tension of the small or supplemental spring *f*.

The arrangement shown in Fig. 2 is substantially the same as that shown in Fig. 55 1 except that the springs *d* and *f* are con-

fined between the spindle flange *o* and the hollow end of the shaft *a* whereby the spindle *b'* is normally maintained in outwardly projected position and is adapted to be moved inwardly incident to turning movement of the motor shaft *a* to engage the pinion *c* with the teeth of the fly wheel *g*, the latter occupying a position intermediate the pinion *c* and the end of the shaft *a*.

60 The nut *i* is detachably connected with the hollow shaft by a screw *w* so as to be interchangeable. Thus nuts having a right-hand thread or a left-hand thread may be employed as required. A disk or ring *k* made of resilient material may be inserted in the hollow shaft and, as in Fig. 1, is confined between the flange *o* and the shaft *a* or, as in Fig. 2, between said flange and the nut *i*, the said disk or ring *k* serving the 70 purpose of absorbing the shocks from the spindle *b'* returning the pinion *c* to its normal position.

75 The operation is as follows: On starting the electric motor to full speed the armature shaft *a* is given so high a circumferential velocity that the pinion *c* and spindle *b'* will be forcibly projected, owing to their inertia, the pinion *c* moving towards the fly-wheel *g*. As both the teeth of the pinion *c* and the teeth of the fly-wheel *g* are cut away and curved or rounded at their engaging ends, and as the light spring *f* only opposes the initial movement of the pinion *c*, the latter at once engages in the toothed rim of 80 the fly-wheel to such extent that no injury is done to the cooperating teeth and their edges are not damaged.

85 Owing to the stopping or retardation of the fly-wheel and the spindle *b'* due to compression of the explosion engine the motor shaft *a* turns relative to the spindle *b'* and the nut *i* acting on the thread of said spindle will cause the spring *d* to be fully compressed so that a complete and smooth engagement between the pinion and the fly-wheel occurs.

95 When the explosion engine starts running, the fly-wheel runs ahead of the rotary speed of the starting motor, whereby the pinion 100 will be compelled, both by the pressure of the re-acting spring *d* and by the rotary power acting in opposite direction to disengage from the fly-wheel and to return into its initial or normal position shown in the 110 drawing.

From the foregoing description, it will be

seen that simple and efficient means are herein provided for accomplishing the objects of the invention, but while the elements shown and described are well adapted to serve the purposes for which they are intended, it is to be understood, that the invention is not limited to the precise construction set forth, but includes within its purview such changes as may be made within 10 the spirit and scope of the appended claims.

What I claim is:

1. A means for coupling an electric starting motor with an explosion engine, comprising a motor shaft, having a hollow end, 15 a nut removably mounted in said hollow end, a threaded spindle engaging in said nut, a pinion rigidly connected with the spindle, and a spring within the hollow shaft end acting to hold the pinion in its 20 normal position and adapted to be compressed when the said spindle with the pinion thereon moves in one direction.
2. A means for coupling an electric starting motor with an explosion engine, comprising a motor shaft having a hollow end, 25 a nut detachably affixed within said hollow end, a threaded spindle engaging in said nut, a pinion rigidly connected with the spindle, and a spring within the hollow shaft.
3. A means for coupling an electric starting motor with an explosion engine comprising a motor shaft having a hollow end, 30 a nut detachably affixed within said hollow

end, a screw-spindle engaging in said nut, a pinion rigidly connected with the spindle, 35 a strong spring and a light spring both housed within the hollow shaft.

4. A means for coupling an electric starting motor with an explosion engine, comprising a motor shaft having a hollow end, 40 a nut detachably affixed within said hollow shaft end, a screw-spindle engaging in said nut, a pinion rigidly connected with the spindle, a spring within the hollow shaft end, and a circular member made of resilient 45 material and embedded in the hollow shaft end.

5. A means for coupling an electric starting motor with an explosion engine, comprising a motor shaft having a hollow end, 50 a nut removably mounted within said hollow shaft end, means detachably securing said nut in position, a screw-spindle engaging in said nut, a pinion rigidly connected with the spindle, a strong spring and a light 55 spring both housed within the hollow shaft end, and a circular member made of resilient material and embedded in the hollow shaft end.

In testimony whereof I affix my signature 60 in presence of two witnesses:

FRIEDRICH MÜNZ.

Witnesses:

AUGUST DIETERICH,
OTTO WAGNER.
